UNITED STATES PATENT OFFICE

FRANCIS H. McCORMICK, OF GLEN ELLYN, ILLINOIS, ASSIGNOR TO EDISON ELECTRIC APPLIANCE COMPANY, OF CHICAGO, ILLINOIS, A CORPORATION OF NEW YORK

COUNTERBALANCE FOR DOORS

Application filed October 12, 1929. Serial No. 399,331.

My invention relates to a counterbalance for doors and like movable members and has for its object the provision of an improved device of this character.

5 More specifically, my invention relates to an improved counterbalance for oven doors and the like. My invention is especially directed to drop oven doors that swing about a horizontal axis, and has for a further object 10 the provision of a counterbalance for the door arranged so that all the parts of the counterbalance are concealed and yet are readily accessible for adjustment, replacement or repair.

15 In accordance with my invention, I provide a strip-like spring mechanically connected with the door so that the spring will be flexed by the opening movement of the door to counterbalance its weight. Preferably, the spring will be curved initially so

20 that it will have a substantially semi-elliptical form when the door is in its closed position. In order to steady the motion of the door I provide auxiliary damping means. I 25 have found that the spring together with the damping means will give the door a steady motion and will cause the door to stand at practically any position in which it has been placed.

30 The spring and likewise its mechanical door connections and the damping means are so positioned that they are concealed by the range structure.

35 For a more complete understanding of my invention reference should be had to the accompanying drawings in which Fig. 1 is an elevation of an electric range embodying my invention; Fig. 2 is an elevation on a larger scale of a portion of the range shown in Fig.

40 1; Fig. 3 is a vertical section taken through line 3—3 of Fig. 2 illustrating the door in its closed position; Fig. 4 is a view similar to Fig. 3 but illustrating the door in its open position; Fig. 5 is an elevation of a portion 45 of an electric range embodying a modified form of my invention, portions of the range being broken away to illustrate certain structural details; Fig. 6 is a vertical section taken through the line 6—6 of Fig. 5 illustrating the door in its closed position; and Fig. 7

is a view similar to Fig. 6 but illustrating the door in its open position.

Referring to the drawings, I have shown my invention in one form as applied to an electric range although obviously any form 55 of heat may be used. As shown, in Figs. 1 to 4 inclusive, the range is provided with an oven compartment 10 on the right hand side, as viewed in Figs. 1 and 2, and with a cooking top 11 on the left hand side. Suitable 60 electric heating elements (not shown) are provided for the oven and cooking top.

It will be understood that the oven heating chamber will be formed from a pair of 65 side walls 12 and 13, an end wall (not shown) and top and bottom walls 14 and 15 so as to form a heating chamber with a front opening. This opening normally is closed by a suitable cover or door 16. It will be observed by reference to Figs. 3 and 4 that the 70 oven walls and also the door are formed from a pair of spaced metallic linings between which a suitable heat insulating material 17 such as rock wool is placed.

A suitable base or frame 18 of angle members 75 formed into rectangular shape is provided for the oven and cooking top. It will be understood that the outer metallic linings provided for the oven walls will be extended downwardly below the bottom wall 80 of the oven to the angular framework to which they will be suitably secured as by screw fastening means (not shown). Thus, the oven will be supported in spaced relation 85 with respect to its supporting framework. Suitable legs 19 are provided to support the framework.

The door 16 is hinged to move about its lower horizontal edge so that it may be swung 90 from a vertical closed position (Fig. 3) to a horizontal open position (Fig. 4). As shown, the hinge structure provided for the door comprises a pair of hinge brackets 20. Each hinge bracket is of bell-crank shape, 95 the arms 20a and 20b of the bell-crank being joined by an arc-shaped arm 20c. As shown, the arms 20a serve to support the door and each is provided with a flanged portion which projects at right angles to the plane 100 of the arms 20a, 20b and 20c, and which is

secured to the door by any suitable means, such as by welding. These flanges as shown are relatively long and relatively wide so as to provide a substantial bearing area 5 against the door.

It will be observed that the bell-cranks 20 are pivotally mounted at their apexes upon a hinge rod 21 which is disposed crosswise of the oven opening and slightly below the 10 surface of the oven floor. This rod is supported by means of a pair of clips (not shown), a clip being located at each end of the rod and both being welded to the oven front plate. In assembling, the rod is pushed 15 into the oven through its side so as to be received by the clips. The curved portion 20c of each bell-crank is passed through a suitable slot-like aperture provided in the door frame. Each of the other arms 20b of 20 the bell-cranks is projected beyond the curved portion 20c so as to form a latch-like member 22 which is arranged to engage an abutment or stop pin 23 when the door has been moved to its full open position. It will be 25 observed that the arms 20a and 20b of each bell-crank form an angle slightly greater than 90° so that the stop pins, which necessarily must be displaced inwardly from the vertical position assumed by the closed door, 30 will permit the door to be moved to a horizontal position when opened.

In order to balance the door so that it will not fall rapidly to its open position by reason of its gravity bias and moreover, in order to 35 cause the door to stand in practically any position to which it has been moved, I provide a suitable counterbalance strip-like spring 24 suitably mechanically connected with the door and suitably supported by the framework. As shown, the spring is curved so that it normally assumes a semi-elliptical shape. The spring is supported by the front angle 40 member of the framework 18 preferably so that its center portion lies directly below one 45 of the hinge bracket members 20. In other words, the spring is positioned so that the vertical plane containing the three arms 20a, 20b and 20c of the hinge bracket will pass substantially through the longitudinal center of 50 the spring. As shown, this spring is thus positioned below the left-hand hinge. This central portion of the spring is mechanically connected with the hinge bracket by means of a vertically disposed tension link 25. As 55 shown, the upper end of this link is mechanically connected with the arm 20b of the bell-crank by means of a pin 26 provided on the tension link and which is arranged to be received by a hook member 27 provided on the 60 arm. The lower end of the tension link is mechanically connected with the spring by means of a clip or saddle 28. This saddle 65 preferably will be of substantially the same width as the spring and will have a length so that a relatively large bearing area will be

provided for the spring. The saddle is provided with upright flange-like members 29 which serve to carry a pin 30 disposed crosswise of the spring. The lower end of the tension link is curved about this pin in hook-like 70 fashion.

The spring 24 is secured at each end to the frame by means of a suitable lost motion connection shown as a pin and slot connection. As shown, this pin and slot connection comprises a bolt-like member 31 secured to the horizontal portion of the front flange of the framework 18, the bolt being passed through a longitudinal slot provided in the end portion of the spring. Preferably, the bolt 31 will be provided with a bushing 32 which is received directly by this slot. Also it is preferable to position a pair of washers 32a on opposite sides of the spring. It will be understood that when the spring is flexed by the opening movement of the door, the frictional forces occurring between each end portion of the spring and the washers positioned between the spring and the frame 18 will provide a considerable damping effect. In other words these frictional forces will serve to steady the motion of the door.

In operation, it will be understood that the door, when it is moved to its open position, will rotate the hinge brackets 20 in a counter-clockwise direction, as viewed in Figs. 3 and 4, and thereby flex the spring 24. The spring, therefore, will exert a resisting or counter-balancing force to the weight of the door. It will be observed that as the leverage of the force of gravity acting on the door is increased by the opening movement of the door, the spring will be subjected to an increasing stress which will serve to substantially balance the increased gravity force. Likewise, when the door is being closed, the spring will serve to counterbalance the weight of the door.

It will be observed that the frictional forces occurring between the end portions of the spring and the supporting structure will serve to steady the motion of the door. By reason of this tendency of the foregoing construction to steady the motion of the door, it will stand at practically any position to which it has been moved.

An important feature of my invention is the arrangement of the hinge and counterbalance construction in that all of the elements are concealed by the range structure. It will be observed by reference to the drawings that the spring 24 is concealed by the depending flange of the framework 24; and the hinge bracket 20, their supporting rod 21 and also the tension link 25 are concealed by the range front plate. However, the hinge and counterbalance elements are readily accessible for replacements, repairs and adjustments. All of these elements may be removed or replaced

without the necessity of employing special tools.

In the event the range be provided with a relatively heavy door, it is sometimes desirable to supply a counterbalance spring 24 for each hinge or to supply only one spring for both hinges. In the latter arrangement the spring will be of semi-elliptical form and will be secured at its central portion to the 10 framework in a position reversed to the position of the spring shown in Fig. 1.

Referring to Figs. 5, 6 and 7, I have shown a modified form of my invention in which a 15 spring arrangement of this character is provided. The oven door 40 of this form, like the door of the first form, shown in Figs. 1-4, is provided with a hinge bracket 41 at each end. These brackets are similar to the brackets provided for the first form in that 20 they have a bell-crank shape. Thus, each bracket has a flanged arm 41a and a second arm 41b arranged substantially at right angles to the first arm and connected thereto by a third arm 41c. Each flange portion 25 41a is secured to the door while each portion 41b is provided with a latch-like projection 42 arranged to engage a suitable stop 43 when the door is in its open position (Fig. 7). The arm portion 41c in the assembled 30 range passes through a suitable slot-like aperture 44 provided in the door frame.

The arm 41b also serves to mechanically connect the door with its counterbalance. This counterbalance comprises a flat strip-like spring 46 which when the door is in its 35 closed position (Figs. 5 and 6) has a semi-elliptical form. As shown, this spring is secured at its central portion to the range, a suitable U shaped bracket 47 being provided for this purpose. One leg of this 40 bracket is secured to the oven supporting frame 48 while the other leg is secured to the bottom outer lining of the oven. It will be understood that the spring will be secured 45 to the bracket by any suitable means. Thus, the spring may be either bolted or welded to the bracket.

The spring 46 is positioned so that with the door in its closed position (Figs. 5 and 50 6), its end portions curve away from the bottom of the oven and as shown, each end of the spring is mechanically connected with the hinge bracket 41b positioned at that end of the oven. As shown, each spring end is connected with its bracket by means of a vertically disposed link 50. This link is passed through an aperture in the end portion of the spring and is provided at its lower end with a head to prevent it from passing there-through. The upper end of the link is bent at right angles to the body of the link and is received in an aperture provided for it in the bracket arm 41b. A suitable pin 51 serves to secure the upper end of the link.

65 It will be observed that by reason of this

construction, a single spring 46 is mechanically connected with both of the hinge brackets and will serve to counterbalance the door throughout both its opening and closing movements. Thus, when the door is opened the ends of the spring will be moved upwardly to the position shown in Fig. 7 and when the door is closed these ends will be returned to their initial positions shown in Figs. 5 and 6. It will be understood that the spring will be sufficiently strong to counterbalance the door between the limits of its entire movement.

Suitable damping means also may be provided in this arrangement. For this purpose I provide a strip-like member 52 positioned substantially coextensive with the spring and below the spring between it and the headed ends of the links 50. The strip-like member is provided with suitable apertures to receive the links 50. The member 52 performs a function similar to the angle support 18 of Fig. 1 in that it frictionally engages the end portions of the spring 46 as it is being flexed by the movement of the door. It will be understood that these frictional forces which occur between the end portions of the spring and the strip like member 52 will serve to damp, i. e. steady the motion of the door.

The hinge brackets 41 of this arrangement instead of being fixedly pivoted to a rod extending across the oven as are the brackets of Figs. 1-4, are provided with separate fixed supports 55 upon which they are removably mounted. Each support 55 is mounted with 100 in a suitable casing 56. It will be understood that this casing also serves to protect the hinge and counterbalance mechanism from the rock wool insulation between the inner and outer linings of the oven.

As shown, the arm 41b of each hinge bracket is provided at its lower end with a hook-like bearing member 57. This member is proportioned so that it may readily be positioned upon or removed from its support 55 but is 110 large enough to provide a sufficient bearing area. It will be understood that in the assembled range the spring counterbalance serves to maintain the door with its brackets secured on their hinge supports.

It will be observed that the arm 41a is mechanically connected with the arm 41b only by means of the portion 41c. In other words the arms 41a and 41b are not mechanically connected at the apex of the right angle but are separated sufficiently at this point to receive the bottom portion of the door frame. It will be understood that by reason of this construction, the door in being opened will be swung downwardly and outwardly clear of the lower portion of the door frame and in being closed will be swung upwardly to be received by the door frame.

This construction is of advantage in that the door may be readily assembled or re-

moved. In order to assemble the door it is merely necessary to project the arms 41b through the slots 44 provided in the door frame and then lower the door slightly so that the hook-like bearing members 57 will be received by their respective supporting rods 55. To remove the door it is merely necessary to disconnect the counterbalance, lift the door from its supporting members 55 and withdraw the arms 41c through the slots.

Moreover, the foregoing bracket and counterbalance construction is of advantage in that all of the parts of the mechanism are concealed. This improves the appearance of the stove. The appearance is further improved in that it is possible by reason of this arrangement of the door supports to shape the lower portion of the door to conform with the upper portion. Thus, the lower corners of the door, as shown, are rounded as are the upper corners.

What I claim as new and desire to secure by Letters Patent of the United States, is:

1. The combination with a member movable between a pair of limiting positions and biased to one of said positions, of a counterbalancing spring cooperating with said member and an auxiliary member frictionally engaging said spring so as to damp the motion of said first member.

2. The combination with a member movable between a pair of limiting positions and biased to one of said positions, a counterbalance for said member comprising a strip-like spring, means mechanically connecting said spring with said member so that said spring is flexed by the movement of said member to said one position and a member having portions thereof defining substantially plane surfaces arranged to frictionally engage portions of a surface of said spring as said spring is flexed by the movement of said member so as to damp the motion of said member.

3. A counterbalance for a member mounted to move between a plurality of positions and biased to move to one of said positions comprising a semi-elliptical spring, means mechanically connecting said spring with said movable member so that said spring is flexed by the movement of said member to said one position to counterbalance said bias and means for supporting said spring to provide for frictional engagement between portions of said spring and said support, said supporting means thereby serving to damp the motion of said member.

4. The combination with an oven or the like provided with walls forming a heating chamber having a front opening therein of a door for said opening, hinge means for pivotally supporting said door at its lower edge so that said door can be moved about a horizontal axis to its open and closed positions,

a counterbalance strip-like spring for said door, means for securing said spring beneath said door, a lever mechanically connected with said door, a link mechanically connecting said lever with said spring so that the spring is flexed by the movement of said door to counteract its weight, and auxiliary means for damping the motion of said door.

5. The combination with an oven or the like provided with walls forming a heating chamber having a front opening therein of a door for said opening, hinge means for pivotally supporting said door so that said door may be dropped to an open position, a counterbalance strip-like spring for said door, lever means for mechanically connecting said door with said strip-like spring, means for supporting said spring so that the spring is flexed by the movement of said door to counteract its weight and a strip-like member for frictionally engaging the ends of said spring so as to damp the motion of said door.

6. The combination with a pivotally mounted member movable between a substantially vertical position and a substantially horizontal position of a counterbalance for said member comprising a lever mechanically secured to said member, a strip-like semi-elliptical spring member, means for supporting said spring member at its end portions, said means providing for relative movement between these end portions and the spring support, and a link mechanically connecting the central portion of said spring and said lever so that the tension of said spring together with the frictional resistance to the movement between said spring and its support counterbalances the weight of said member to maintain the member in any position between its limits of movement.

7. The combination with a normally closed oven door or the like of a plurality of bell-crank hinge members for said door, means for securing said door to corresponding arms of said bell-cranks, means for pivotally mounting said bell-cranks so that said door may be swung from a vertical closed position to a horizontal open position and counterbalancing means for said door comprising a spring normally semi-elliptical, means mechanically connecting the central portion of said spring with the free arm of one of said bell-cranks and means for supporting said spring at its end portions so as to provide for freedom of movement between said spring and its supporting means.

8. An oven comprising walls forming a heating chamber, said heating chamber being provided with a front opening therein, supporting means for said heating chamber comprising a structural framework, said framework being provided with a depending flange, a door for said opening, hinge means pivotally mounting said door so that it may be moved from a vertical closed position to

- a horizontal open position, said hinge means comprising a bell-crank to one arm of which said door is secured, means for pivotally mounting said bell-crank, a strip-like spring connected to the other arm of said bell-crank so as to counterbalance the weight of said door, said spring being embraced by said depending flange and said connecting means being concealed by the oven support-
10 ing means and means also embraced by said depending flange for frictionally engaging the end portions of said strip-like spring so as to damp the motion of said door.
9. The combination with a stove provided with walls forming an oven chamber having a front opening therein of a plurality of horizontally disposed angle members connected to form a supporting frame for said walls upon which the walls are supported in spaced relation, said framework having a peripheral depending flange, hinge means pivotally mounting said door for swinging motion from a vertical closed position to a horizontal open position, said hinge means comprising a pair of bell-crank hinge arms, means for securing said door to corresponding arms of said bell-cranks so that said door is secured on one side of the pivotal axis of said bell-cranks, a hook mounted on the other arm of one of said bell-cranks on the other side of said pivotal axis, a strip-like counter-balancing spring for said door, means for supporting said spring at its end portions to one of said angle members lengthwise of the member so that the spring is concealed by said depending flange, said end supports providing for limited relative movement between said spring and its supporting frame, and a tension link mechanically connecting said hook and the central portion of said spring, said spring being initially curved so as to assume a substantially semi-elliptical form with the door in its vertically closed position.
40
10. The combination with a pivotally mounted member biased to move in one direction of a counterbalance for said member comprising a spring member and means for mechanically connecting said spring member with said pivotally mounted member at a plurality of points so that said spring exerts a force in a direction to counterbalance said bias and an auxiliary member frictionally engaging said spring so as to damp the motion of said first member.
50
11. The combination with an oven provided with walls forming a heating chamber having a front opening therein of a door for said opening, a pair of hinge brackets for pivotally supporting said door so that said door can be swung about a horizontal axis to its open and closed positions, a counterbalance strip-like spring for said door, means for securing said spring at its central portion beneath said pivotal axis so that the ends of said
- spring are substantially in vertical alignment with said hinge brackets respectively, link members for mechanically connecting the ends of said spring with said hinge brackets respectively so that said spring is flexed by the movement of said door to thereby counterbalance the weight of said door, and means for frictionally engaging the end portions of said spring so as to damp the motion of said door.
70
12. The combination with an oven provided with walls forming a heating chamber having a front opening therein of a door for said opening, a pair of hinge brackets pivotally supporting said door so that it may be dropped to an open position, a counterbalance strip-like spring for said door, means for securing said spring at its central portion so that each end of said spring is positioned beneath one of said hinge brackets and so that said spring assumes a semi-elliptical form with the door in its closed position, link members for connecting the ends of said spring with said hinge brackets, and means for damping the motion of said door comprising a strip-like member positioned below said spring and secured so that it will frictionally engage the end portions of said spring.
80
13. The combination with an oven or the like having walls forming an oven chamber with a front opening therein of a door for said opening, means for pivotally supporting said door for movement about a horizontal axis comprising a fixed support at each end of said door and positioned behind the oven front plate, a bracket secured to said door at each end, said brackets being provided with extending arms formed to pass through openings in the oven door frame and each being provided with a bearing portion to rest on its corresponding fixed support, a strip-like spring member supported below the horizontal axis of said door, and means for mechanically connecting said spring member with said brackets so that said spring member operates to hold said brackets on their respective fixed supports, and to counterbalance the weight of said door, and auxiliary means comprising a strip-like member for frictionally engaging portions of said spring member so as to damp the motion of said door.
90
14. The combination with an oven or the like provided with walls forming a heating chamber having a front opening therein of a door for said opening, a pair of hinge brackets for pivotally supporting said door at its end portions so that said door can be swung about a fixed horizontal axis to its open and closed positions, a strip-like spring for said door, means for securing said spring at its central portion beneath said pivotal axis so that the longitudinal axis of said spring is substantially parallel with said pivotal axis, said spring being substantially co-extensive with said door so that its ends are
100
- 110
- 115
- 120
- 125
- 130

in substantial vertical alignment with said hinge brackets respectively, link members connecting the ends of said spring with said brackets respectively so that said spring is flexed by the movements of said door to its open and closed positions to thereby counter-balance the weight of said door, and a member frictionally engaging portions of the area of a surface of said strip-like spring so as to damp the motion of said door.

10 In witness whereof, I have hereto set my hand this seventh day of October, 1929.

FRANCIS H. McCORMICK.
